UNITED STATES PATENT OFFICE.

PAUL H. SCOTT, OF LYNN, MASSACHUSETTS, ASSIGNOR TO GENERAL ELECTRIC COMPANY, A CORPORATION OF NEW YORK.

GOVERNING MECHANISM FOR PRIME MOVERS.

Application filed February 26, 1925. Serial No. 11,880.

To all whom it may concern:

Be it known that I, PAUL H. SCOTT, a citizen of the United States, residing at Lynn, in the county of Essex, State of Massachusetts, have invented certain new and useful Improvements in Governing Mechanism for Prime Movers, of which the following is a specification.

The present invention relates to governing mechanisms for prime movers such as elastic fluid turbines. In such governing mechanisms there is provided usually a means for adjusting the mechanism so as to set it for the desired speed, such a means in the case of turbines being termed usually a synchronizing means in that it is utilized in synchronizing alternating current machines connected to the same busbars. Such a means is usually operated by a reversible electric motor termed a synchronizing motor. The primary object of my invention is to provide an improved construction and arrangement for effecting this adjustment.

For a consideration of what I believe to be novel and my invention, attention is directed to the accompanying description and the claims appended thereto.

In the drawing, Fig. 1 is a diagrammatic view partly in section of a governing mechanism embodying my invention; Fig. 2 is a sectional view on a larger scale of a part of the mechanism shown in Fig. 1; Fig. 3 is a sectional detail view on a larger scale than Fig. 2 of certain of the parts shown therein; Fig. 4 is a detail sectional view taken on line 4—4, Fig. 3, and Fig. 5 is a detail view of a part of the governing mechanism.

In connection with the drawing, it is pointed out that my invention is shown as applied to a valve gear of the general type of that shown in the application of Edgar D. Dickinson, Serial No. 692,615, filed February 13, 1924. However, it is to be understood that it is not necessarily limited to use with this particular type of valve gear although as to certain aspects it is particularly well adapted for such use.

Referring to the drawing, 5 indicates the admission end of an elastic fluid turbine to which elastic fluid is admitted by suitable valve means 6 which is opened and closed by turning movements of a cam shaft 7. The turbine shaft is indicated at 8 and the oil tank at 9. The illustration of the turbine in Fig. 1 is wholly diagrammatic. The

turbine casing 5 and shaft 8 are not shown in correct relation to each other but the turbine casing is brought around into the plane of the paper in order to illustrate more clearly the arrangement of the governing mechanism and its connection to the turbine. On the end of cam shaft 7 is a pinion 11 which meshes with a rack 12 formed on the upper end of a rod 13. The lower end of rod 13 is connected to a piston 14 located in a cylinder 15 and biased towards the bottom of the cylinder by a spring 16 located between the top surface of the piston and a spring plug 17 fastened to the upper end of cylinder 15. The arrangement is such that when piston 14 moves upward it opens valve means 6 and when it moves downward it effects closing of such valve means. The detail structure of the valve means is not illustrated as it forms no part of the present invention. Any suitable valve means arrangement adapted to be opened and closed by movements of rod 13 may be used. The particular valve means indicated in the drawing is that which forms the subject matter of the application of Dickinson and Standerwick, Serial No. 692,601, filed February 13, 1924.

On turbine shaft 8 is a worm 18 which meshes with a worm wheel 19 mounted on a vertical shaft 20. Shaft 20 is mounted in suitable bearings, one of which is indicated at 21, and at its lower end is connected to drive an oil pump 22 located in tank 9. Pump 22 takes oil from tank 9 through a suitable intake strainer 23 and delivers oil through a conduit 24 to a pipe 25. Connected to pipe 25 is a pressure relief valve 26 which discharges back to tank 9 and which is set to maintain in pipe 25 a certain desired pressure. Pipe 25 delivers oil through an orifice 27 in a plate 28 to a pressure pipe 29 and a by-pass pipe 30 which branches therefrom. Since there is a constant pressure in pipe 25 oil will be delivered through orifice 27 to pipes 29 and 30 always at a definite rate depending upon the pressure existing in such pipes. Pipe 29 is connected to cylinder 15 beneath piston 14 and conveys pressure to the underside of the piston for effecting operation of the valve means 6. By-pass pipe 30 is connected to an annular chamber 31 formed in a pilot valve casing 32. In casing 32 is a bushing or sleeve 33 provided with ports

34 located in alignment with chamber 31. Bushing 33 extends well beyond chamber 31 at each end and is connected at its upper end to a cylindrical head 35 by means of bolts 36. Head 35 is provided at its upper end with a threaded opening 37 in which is located a threaded stud 38. On stud 38 are two spaced stops 39 and 40 and on the top of head 35 are two stops 41 and 41^a adapted to engage with stops 39 and 40, respectively. In pilot valve casing 32 is a shoulder 42 upon which rests the lower end of a worm wheel 43 carried by a sleeve 44. Sleeve 44 is held in position by a cap piece 45 which is fastened in the top of pilot valve casing 32 by bolts 46. Cap piece 45 forms a bearing for sleeve 44 in which the sleeve is adapted to turn. Cylindrical head 35 has a sliding fit in sleeve 44 and the two are attached together in such a manner that while head 35 can move axially up and down in sleeve 44 it cannot turn therein. To this end sleeve 44 is provided with a vertical groove 44^a in which lies a key 44^b carried by head 35. Connected to the upper end of stud 38 is a rod 47 which projects out beyond the top of the pilot valve casing and has a hand wheel 48 fixed on its end. At the point of connection between stud 38 and rod 47 is a shoulder 49 upon which rests the lower end of a sleeve 50 which has a sliding fit in sleeve 44. The lower end of sleeve 50 is provided with an end wall 51 through which rod 47 projects and surrounds rod 47 and resting on such end wall is a thrust washer 52. Thrust washer 52 fits loosely on rod 47 and is held against wall 51 by a spring 53 which is compressed between washer 52 and a plug 54 which forms a part of hand wheel 48. Thrust washer 52 is attached to rod 47 by a key 55 which is carried by the rod and fits somewhat loosely in a vertical groove 56 in the washer. Rod 47 can thus move axially through washer 52 but cannot turn relatively thereto. Rod 47 fits somewhat loosely in the opening in wall 51 but is connected to wall 51 by the frictional engagement between such wall, the shoulder 49 and thrust washer 52. In other words, spring 53 serves to squeeze wall 51 between thrust washer 52 and shoulder 49, thereby forming a frictional connection between rod 47 and sleeve 50.

55 On the outer end of sleeve 50 are trunnions 50^a which engage furcations 57^a on the ends of arms 57^a carried by a bell crank lever 57. Lever 57 is pivoted at 58 on a fixed arm 59 and is counterbalanced by a weight 60. Lever 57 is connected by a rod 61 to a head 62 which slides in a guide 63 and has a roller 64 on its end pressed by a spring 65 into engagement with a cam 66 on cam shaft 7.

66 Meshing with worm wheel 43 is a worm

67 carried by a shaft 68 journaled in the wall of casing 32. On the outer end of shaft 68 is a worm wheel 69 which meshes with a worm 70 on the shaft of a synchronizing motor 71. Motor 71 is suitably mounted in a cradle 72 carried by casing 32, and is adapted to be controlled by a suitable reversing switch 72^a.

Inside bushing or sleeve 33 is a pilot valve 73 which is in the form of a tube and is connected at its lower end directly to the weight arms of a centrifugal speed governor so as to turn therewith. To this end sleeve valve 73 is fastened to an upper spring plug 74 which is connected to a lower spring plug 75 by a spring 76. The lower spring plug is provided with a stirrup 77 in which the ends of governor weight arms 78 lie, the end of the arms overlapping each other. The under arm end is pivotally connected to the stirrup by a pin 79. The upper arm end is provided with a pivot bearing 80 between which and a pivot bearing 81 on spring plug 74 is located a pivot rod 82. The engaging surfaces of the overlapping ends of arms 76 are curved so as to rock on each other and are kept in engagement with each other by pivot rod 82 which is held in its pivot bearings by spring 76. The governor weight arms 78 are pivoted on the arms of a yoke 83 by pin bearings 84 and the governor weights which are indicated at 85 are connected to each other by a governor spring 86. Yoke 83 is fastened directly to the upper end of shaft 20. Spring 76 forms a driving connection between pilot valve 73 and the governor so that the pilot valve turns with the governor, and in conjunction with pivot rod 82 forms a connection between the pilot valve 73 and the governor for transmitting axial movements from the governor to the pilot valve.

When the turbine is running, oil pump 22 maintains a definite pressure in pipe 25 and the oil flowing through orifice 27 maintains a definite pressure in pressure pipe 29 and by-pass pipe 30 depending upon the extent to which ports 34 are uncovered by pilot valve 73, it being understood that when ports 34 are uncovered oil can escape from pipe 30 through ports 34 and the inside of pilot valve sleeve 73 to tank 9. The pressure in pressure pipe 29 acts on the underside of piston 14 and holds it against the action of spring 16 in a position wherein valve means 6 is opened to the extent required to maintain the desired speed. If now the speed increases the speed governor weights 85 will move out thus lowering pilot valve sleeve 73 and uncovering further ports 34. This permits the more rapid escape of oil from pipe 30 through ports 34 thereby effecting a decrease in the pressure in pipe 29 and that under piston 14 whereupon spring 16 forces piston 14 downward, thereby turning cam 130

shaft 7 to close somewhat valve means 6 so as to decrease the supply of elastic fluid to the turbine. When cam shaft 7 turns it turns also the cam 66 in a direction to permit spring 65 to move rod 61 toward the left as seen in Fig. 2. This turns bell crank lever 57 in a direction to force sleeve 50 downward somewhat and when sleeve 50 moves downward it carries with it stud 38 and bushing 33. The downward movement of bushing 33 serves to move ports 34 toward pilot valve 73 so as to close the ports somewhat and prevent overtravel or hunting of the valve mechanism. With decrease in the supply of elastic fluid the turbine returns to normal speed again. In case of a decrease in the turbine speed, then a similar operation takes place in the opposite direction to effect further opening of the valve means so as to bring the speed back to normal. The bushing or sleeve 33 connected to rod 61 in conjunction with pilot valve sleeve 73 takes the place of the usual follow-up connection for the pilot valve and operates to produce the same result.

With the above construction it will be noted that the pilot valve 73 is connected directly to the governor and revolves therewith. This keeps the pilot valve continuously in motion so that there is no danger of its becoming stuck. The pilot valve 73 may be made very light in weight so that it places very little load on the governor weights and but little force is required to move it axially. As a result the governor is required to do but very little work so that it may be made small and extremely simple and sensitive.

Referring now to the adjustment of the governing mechanism for different speeds, this is accomplished by changing the setting of bushing or sleeve 33 relatively to the speed governor and pilot valve 73. Assume for example that the turbine is operating at a certain normal speed and that it is desired to set it for a higher speed. This is done by lowering bushing 33 relatively to pilot valve 73 so as to close somewhat ports 34 which results in the building up of the pressure in pipe 29 and a further opening of valve means 6. The turbine will then increase in speed and governor weights 85 will thereupon assume a new position drawing down pilot valve 73 until equilibrium is established at a new and higher speed. To set the governor for a lower speed bushing 33 is raised relatively to pilot valve 73 thereby opening further ports 34 which effects a decrease in the pressure under piston 14 whereupon it is lowered and valve means 6 closed somewhat. The speed of the turbine then decreases and the speed governor assumes a new setting at the same time raising pilot valve 73 until equilibrium is again restored.

The movement of bushing 33 for setting the speed of the machine is effected by means by synchronizing motor 71 which may be controlled by a suitable switch in the usual and known manner, it being understood that motor 71 is a known type of reversing motor. When motor 71 runs in one direction it turns sleeve 44 one way and when it runs in the other direction it turns the sleeve the other way. When sleeve 44 turns, it carries with it head 35 and bushing 33 because of the groove and key connection 44^a, 44^b. Stud 38 is held from turning normally due to its frictional connection with sleeve 50 so that as head 35 turns it will be driven up or down on the threads or stud 38 according to the direction of rotation thereby raising or lowering bushing 33. The travel of head 35 on stud 38 is limited by the stops 39 and 40, such stops being engaged by stops 41 and 41^a on the head when the upper and lower limits are reached. When either pair of stops comes into engagement, continued vertical movement of head 35 is arrested and if further operation of the motor in the same direction takes place then, due to the engagement of the stops, stud 38 and rod 47 will be turned along with head 35 and bushing 33, the frictional connection between stud 38 and sleeve 50 slipping. By the use of this frictional connection, I avoid either stalling the motor or the use of limit switches for the motor circuit and I consider this feature one of the important ones in my invention.

By the above described construction it will be seen that the follow-up mechanism and the synchronizing mechanism for the governing mechanism are embodied in a single structure which is compact and comparatively simple in arrangement and operation. At the same time it is sensitive and reliable in operation.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. In a governing mechanism, the combination of a regulating valve means, a fluid-actuated motor including a pilot valve structure for actuating said valve means, a governor connected to the pilot valve structure, means for effecting adjustment of the setting of the governor, a motor, adjusting means including a frictional connection, through the intermediary of which adjusting means said motor moves said means for effecting adjustment of the setting of the

governor, and stops for limiting the movements of said last-mentioned means.

2. In a governing mechanism, the combination of a regulating valve means, a fluid-actuated motor including a pilot valve structure for actuating said valve means, a governor connected to the pilot valve structure, means for effecting adjustment of the setting of the governor, said means comprising two members in threaded engagement with each other and one of which is held frictionally from turning, a motor connected with the other member for turning it to cause it to move on the first member, and stops for limiting the movement of such other member on the first member.

3. The combination with a governing mechanism comprising a regulating valve means, a fluid-actuated motor including a pilot valve structure for actuating said valve means, and a governor connected to the pilot valve structure, of means for effecting adjustment of the setting of the governor, said means comprising a threaded member, frictional means for holding it from turning, a second threaded member on the first

member, a sleeve, a key and slot connection between the second threaded member and the sleeve, a motor for turning said sleeve to effect movement of the second threaded member along the first threaded member, and stops for limiting the extent of such movement.

4. In a governing mechanism comprising an axially movable member for effecting adjustment of the setting of the mechanism, the combination with such axially movable member of two engaging threaded members, one of which is attached to said axially movable member, means for holding the other threaded member frictionally from turning, a motor, means connecting the motor to the threaded member which is attached to the axially movable member for turning it whereby there is effected axial movement of it, and stops on the threaded members for limiting such axial movements, said two threaded members both turning when the stops are in engagement.

In witness whereof, I have hereunto set my hand this 24th day of February, 1925.

PAUL H. SCOTT.
